UNITED STATES PATENT OFFICE.

ARTHUR JAMES HURD, OF WAUSAU, WISCONSIN, ASSIGNOR TO WILSON & HURD MANUFACTURING CO., OF WAUSAU, WISCONSIN.

MILK-PAIL HOLDER.

No. 874,078.

Specification of Letters Patent.

Patented Dec. 17, 1907.

Application filed February 26, 1907. Serial No. 359,340.

To all whom it may concern:

Be it known that I, ARTHUR JAMES HURD, a citizen of the United States, residing at Wausau, in the county of Marathon and 5 State of Wisconsin, have invented a new and useful Milk-Pail Holder, of which the following is a specification.

This invention relates to milk pail holders and its object is to provide a durable and 10 efficient and inexpensive device of this character which can be readily adjusted to pails of different sizes.

Another object is to provide a device which can be comfortably supported by the 15 knees of the user and which has simple and effective means for securing it upon a pail.

A still further object is to provide a coupling device of novel form for adjustably connecting the parts of the holder, all of said 20 parts being held against displacement.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a perspective view of the holder; Fig. 2 is an enlarged vertical longitudinal section through one of the 30 couplings; Fig. 3 is a section on line $x-x$, Fig. 2; and Fig. 4 is a section on line $y-y$, Fig. 2, showing the reduced end of one of the members within the coupling.

Referring to the figures by characters of 35 reference, 1, 1 are oppositely disposed similar bowed wires each of which is preferably made of stiff spring metal and has its middle portion folded to form an arched loop 2.

40 That portion of the loop adjoining the bowed part of the wire is twisted as indicated at 3 so as to prevent spreading of the loop. A flat metal strip 4 is arranged upon the lower face of the loop 2 and has its edge portions bent 45 around the wire as shown at 5 so that the strip is securely fastened to the loop and held against displacement. One end of the bowed wire has a laterally extending eye 6 thereon while the other end is flattened as 50 shown at 7 and has its extremity bent inward as indicated at 8. A coupling member is provided for securing the ends of the two wires 1, 1 together and said member preferably consists of a metal block 9 having a key-hole slot 10 therein the narrow portion of

which receives the flattened end 7 of one wire while the larger portion of the opening receives that end of the other wire carrying the eye 6. The bent portion 8 of the wire prevents it from being withdrawn from the 60 coupling as long as the flattened portion 7 is seated in the narrow part of the slot 10. A set screw 11 extends into the large portion of the slot 10 and is designed to bear against the wire end in said large portion and clamp 65 said end against the adjoining flattened portion 7. The two wire ends are therefore securely bound together. Obviously neither end of either wire 1 can be withdrawn from the two couplings 9 because the eye 6 is 70 formed at one of said ends whereas the other end is flattened and bent inward as shown at 8.

A spring catch is secured to each of the wires 1 adjacent the center thereof and consists of a wire 12 having a head 13 at one end while its other end is coiled about the wire 1 and the twisted portion 3 in such a manner as to prevent the catch from shifting out of proper position.

When the parts herein described are to be assembled, the flattened ends of the wires 1 are inserted into the coupling members 9 and then pressed into the small or narrow portions of the slots 10. The other ends of the 75 wires are then inserted into the slots after which said ends are bent around the adjoining wire to form the eyes 6. The parts are then securely held against displacement and none of them can become detached. To 80 fasten the holder to a pail the same is slipped thereover and after the set screws 11 have been loosened the two bowed members 1 are adjusted toward each other so as to bind upon the pail at a point near the top thereof 85 after which the members are locked together by means of the set screws. The heads 13 are then sprung into engagement with the top of the pail and the holder is therefore securely fastened thereto. The bowed loops 90 100 are designed to be placed upon the knees of the operator and hold the pail suspended therebetween. The strips 4 prevent the wire loop from causing discomfort to the user.

Importance is attached to the particular means for permanently fastening the bowed members together and at the same time permitting adjustment thereof.

It will be seen that the device can be made 105 110

at slight cost, is very durable and can be quickly placed upon or removed from a pail.

What is claimed is:

1. In a pail holder the combination with a coupling block having a keyhole slot therein; of oppositely disposed wire members, one of said members having a flattened end portion disposed within the contracted portion of the slot, the extremity of said end portion being bent to prevent withdrawal, and the other member being extended through the larger portion of the slot to support the flattened end portion within the contracted part of the slot and terminating in an eye surrounding the first mentioned member.
2. In a pail holder the combination with a coupling block having a keyhole slot therein; of oppositely disposed wire members, one of said members having a flattened end portion disposed within the contracted portion of the slot, the extremity of said end portion being bent to prevent withdrawal, and the other member being extended through the larger portion of the slot to support the flattened end portion within the contracted part

of the slot and terminating in an eye surrounding the first mentioned member, means for binding together those portions of the members within the slot, an arched loop integral with and extending upwardly and outwardly from each member, and a flat protecting strip secured to the lower faces of and conforming in contour with each of the loops.

3. A pail holder comprising oppositely disposed similar non - detachable members, means for securing said members in adjusted position, arched loops between the end portions of and integral with the bowed members, said loops extending upwardly and outwardly from the members and being twisted adjacent said members, and flat knee protecting strips secured upon the lower faces of and conforming in contour with the loops.

In testimony that I claim the foregoing as my own, I have hereto affixed my signature in the presence of two witnesses.

ARTHUR JAMES HURD
